UNITED STATES PATENT OFFICE.

PHILIP HAAS, OF DAYTON, OHIO.

WATER CLOSET.

Application filed March 21, 1922. Serial No. 545,407.

To all whom it may concern:

Be it known that I, PHILIP HAAS, a citizen of the United States, residing at Dayton, in the county of Montgomery and State of Ohio, have invented certain new and useful Improvements in Water Closets; and I do hereby declare the following to be a full, clear, and exact description of the invention, such as will enable others skilled in the art 10 to which it appertains to make and use the same.

My invention consists in the novel features hereinafter described, reference being had to the accompanying drawings, which illustrate one embodiment of the same, selected by me for purposes of illustration, and the said invention is fully disclosed in the following description and claims.

One of the objects of my invention is to 20 provide the closet bowl with a rim flushing passage having discharge apertures located all the way around the bowl, the rim flush being so constructed that a minimum water supply may be furnished to a certain portion only of the rim passage and the discharge apertures therefor, for the purpose of keeping the adjacent portion of the wall of the bowl wet without the necessity of furnishing sufficient water to supply all of the 25 discharge passages of the rim flush, which would result in an unnecessary consumption of water, a maximum supply of water being provided which may be independently furnished to the rim flush for the purpose of insuring the normal flushing discharge through 30 all of the discharge passages of the rim, when desired. I conveniently effect this action of the flushing rim by providing the rim flushing passage, preferably at opposite 35 sides of the bowl and between the front and rear portions thereof with dams located in the bottom of the passage and being of less height than the passage itself. In connection with the rim so constructed I provide 40 a minimum water supply passage adapted to supply water to the rear portion of the rim in small volume sufficient to discharge through the discharge apertures of the rim in rear of the dams, without overflowing the 45 latter, thus confining the minimum water supply to the rear portion of the bowl, and I 50 also provide a maximum water supply passage adapted to discharge a larger volume of water into the rim passage which will overflow these dams and supply water to all of the discharge openings in the rim. The bowl is also provided with a ventilating jet at the bottom, in line with the discharge passage of the bowl. As this jet is formed of metal I connect the jet supply pipe to the porcelain bowl by means of a spud in such manner as to make a tight joint, and this spud is provided internally with an adjusting device removable from the exterior without interfering with the water connection, the said removable device being provided with throttling apertures for adapting the jet to the particular water pressure available in connection with the closet. These 55 adjusting devices are furnished with throttling apertures of different size, or the throttling apertures therein may be increased in size and number for the purpose of adapting the jet to the particular water pressure available, and the throttling device may also be 60 withdrawn for cleaning if desired or necessary. My invention also comprises means which bring into action simultaneously the water supply for the jet and the minimum water supply to the rim flushing passage for 65 the purpose of ventilating the bowl and wetting the rear portion of the wall thereof when desired, while holding the main or maximum supply for the rim flushing passage closed. When desired the maximum supply to the rim flushing passage may be 70 brought into operation simultaneously with the supply to the jet and simultaneously with the operation of the minimum supply if desired, so as to secure a very complete 75 and thorough flushing action.

In carrying out my invention, I prefer to employ a controlling valve mechanism for the various water passages, such as is herein shown and described, said valve mechanism 80 being adapted to be controlled either manually or by the depression of the seat, but preferably manually, and operating so as to produce the proper sequence of ventilating and flushing operations.

According to my invention, the bowl is 85 also provided at its rear portion with a ver-

tically disposed water passage leading downwardly from the maximum water supply for the rim flush and discharging upwardly and rearwardly into the main discharge of the 5 bowl, for the purpose of facilitating the flushing action and cooperating with the other flushing elements.

In the accompanying drawings,

Fig. 1 represents a perspective view of 10 a water closet of the type known as wall closets embodying my present invention.

Fig. 2 represents a vertical longitudinal sectional view of the same.

Fig. 3 is a vertical transverse sectional 15 view of the same.

Fig. 4 is a detail sectional view of the form of controlling valve mechanism herein illustrated, showing the valve in normal or closed position.

20 Fig. 5 is a similar view showing the valve in open position for supplying water to the jet and to the minimum supply passage for the rim flush.

Fig. 6 represents a horizontal sectional 25 view of a portion of the bowl showing the valve mechanism in section, and illustrating the means for holding the valve in operative relation with the bowl.

Fig. 7 is an enlarged detail sectional view 30 of the ventilating jet showing the removable regulating device therefor.

Fig. 8 is a detail perspective view of one of the said regulating devices detached.

Fig. 9 is a detail of the valve pin controlling the passage between the water inlet chamber and the back pressure chamber.

In the embodiment of my invention herein shown and described, which has been selected by me for purposes of illustration. 1 40 represents the closet bowl, which in this instance is of the type adapted to fit against the wall and be supported therefrom without any connection with the floor, although it is to be understood that my invention is 45 equally applicable to the type of bowl which is supported from the floor. In the present instance the bowl is provided with an attaching flange, 2, adapted to be connected by threaded studs, 3-3, and nuts, 4, 5, with a 50 flange, 6, secured to or preferably forming a part of the vertical soil pipe, 7, and surrounding the lateral aperture, 8, in the pipe communicating with the discharge passage of the bowl, a tight joint between the bowl 55 and the pipe, 7, being effected by means of a sleeve, 9, and gasket, 10, for example. The bowl itself is provided with a rim flushing passage, 11, extending entirely around the bowl and provided at intervals with discharge apertures, 12, in the usual manner.

13-13 represent vertically disposed obstructions or dams, see Figs. 2, 3 and 6, located in the bottom of the rim passage, 11, and being located at opposite sides of the bowl be- 60 tween the front and rear portions thereof,

as clearly indicated in the drawings, the said dams separating the lower portion of the rim passage into front and rear portions. The bowl is also provided with a transversely disposed passage, indicated at 14, which I 70 term the maximum water supply passage for the rim, and which communicates with the rim by an aperture, 15, see Figs. 2 and 6.

The transverse maximum supply passage, 14, connects with a discharge pipe, 16, projecting from the body of the controlling valve mechanism, indicated at 17, and I prefer to connect the valve mechanism to the bowl so as to make a tight joint with the pipe 16, and support the valve in operative 80

position with respect to the bowl by means of a hollow clamping rod or tube, 18, which has a threaded connection within the valve body, as indicated at 19, and extends axially through the pipe, 16, and through the trans- 85

verse passage, 14, from one side of the bowl to the other. The pipe, 16, is provided with a flange, 20, and gasket, 21, to engage the side wall of the bowl adjacent to the passage, 14, therein and the other end of the 90

hollow clamping tube, 18, is provided with a clamping nut, 22, and gasket, 23, which engage the bowl on the other side, thus making a tight joint at opposite ends of the 95

transverse passage, 14, of the bowl, and se- 100

urely holding the valve mechanism in po- 105

sition in operative relation with the bowl. The tubular clamping device, 18, is provided adjacent to the center of its length with a discharge aperture, 24, which is directed to- 110

ward the aperture, 15, which forms the com- 115

munication between the maximum water supply passage, 14, and the rim passage, 11, and means are provided, as hereinafter de- 120

scribed, for introducing the minimum water supply through the hollow clamping device, 18, which forms the minimum supply pas- 125

sage, so that the water will be discharged through the aperture, 15, from the tube, 18, into the rim passage in sufficient quantity 130

to supply the discharge passages, 12, in rear of the dams, 13, without overflowing the 135

dams.

25 represents the main discharge passage of the bowl which is separated from the rear portion of the bowl proper by a vertically disposed partition, 26, in which is formed a vertical water passage, 27, having a dis- 140

charge, 28, at its lower end directed up- 145

wardly and rearwardly into the main dis- 150

charge passage, 25, of the bowl. The ver- 155

tical passage, 27, communicates at its upper 160

end with the transverse maximum supply 165

passage, 14, before described, and will re- 170

ceive water therefrom during the maximum 175

supply to the rim flush. The lower part of 180

the bowl is provided with a ventilating jet, 185

the construction of which is illustrated in 190

detail in Fig. 7.

Where jet connections have been used with 195

earthenware closet bowls, such as is illustrated herein, for example, considerable difficulty has been experienced in making the proper connections for the reason that an aperture of the necessary small diameter for the jet cannot be made practical in the earthenware, and there is considerable difficulty in connecting a jet nozzle in such a manner as to effect a tight joint and yet permit of making the necessary pipe connections from the outside and more particularly securing the desired regulation of the jet in proportion to the water supply, the pressure of which varies materially in different installations. Obviously a jet which would operate satisfactorily with a water pressure of 25 or 30 pounds is not suitable for an installation where the water pressure is 60 to 80 pounds, and vice versa. In accordance with my invention, I provide the lower part of the bowl at a point in alignment with the discharge passage, 25, with an aperture, 29, of considerable diameter, say $\frac{3}{4}$ ", for example, which can be readily molded in the earthenware. The jet nozzle comprises a metallic spud or sleeve, 30, provided at its inner end with a lateral flange, 31, which preferably engages a recess, 32, countersunk in the earthenware at the inner end of the aperture, 29, so as to avoid any projection on the innerside of the bowl. The spud or sleeve, 30, is provided with an exteriorly threaded portion, indicated at 33, to receive a rubber washer, 34, a metal washer, 35, and a nut, 36, by means of which the spud is securely clamped to the earthenware and firmly held in position. In order to supply water to the interior of the sleeve or spud, it is provided with lateral inlet apertures, 37, below the clamping nut, 36, and a water connection, 38, is provided which has a sleeve portion, 39, adapted to surround the spud, and carrying a washer at either end, as indicated at 40-41, the sleeve member, 39, being held in position by a cap nut, 42, which engages the lower end of the spud. The sleeve member, 39, of the water connection, 38, permits it to be adjusted around the axis of the spud, as will be readily understood. For the purpose of regulating the passage of the water through the jet according to the pressure of the water supply, I preferably employ a detachable regulating stem, one of which is illustrated in detail in Fig. 8. This comprises a shank portion, 43, of less diameter than the interior of the spud, a perforated head, 44, at one end of the said shank, and a threaded screw portion, 45, having a slot or other means by which it can be turned, the threaded portion being adapted to engage an interiorly threaded portion at the outer end of the spud, as clearly shown in Fig. 7. When screwed into its proper position, this device will have the inner face of the perforated head, 44, flush with the face of the flange, 31, of the spud, and the head 44 is provided with a plurality of apertures of such number and size as to secure the desired results with a given water pressure. I prefer to provide a plurality of these adjusting devices having their heads 44, provided with apertures of different sizes, according to the usual water supply pressures available in places where these closets are to be installed. In setting the closet, the operator will select a regulating device suitable for the required water pressure, and when it is placed in position the jet will function properly with that pressure. If it should be found that the correct pressure is either greater or less than that for which the device was originally set, it is only necessary to remove the cap, 42, and take out the adjusting device and insert another, the holes in the head of which are of the required size. Obviously if the operator was not provided with a full set of these adjusting devices, the jet could nevertheless be readily adjusted by increasing the size of the apertures in the head if the pressure was too low to give the desired results, or by soldering up certain of the apertures in case the pressure was too great for the particular adjusting device installed, but I prefer to provide the jet with the particular adjusting device having its head, 44, drilled with the holes, 46, especially designed for use with a given water pressure. By providing the porcelain or earthenware bowl with a relatively large aperture to receive the jet, and by employing the construction just described and illustrated in detail in Fig. 7, it will be seen that a very tight and strong connection will be made between the spud and the earthenware bowl, and that the water connections for the jet are entirely outside of the bowl and readily accessible and that the means herein described for regulating the jet are also readily accessible from the exterior of the bowl for adjustment or repair.

As before stated, my invention comprises means for simultaneously admitting water to the jet for ventilating purposes and to the minimum water-supply for the rim flush, for the purpose of wetting down the rear portion of the wall of the bowl during the operation of the jet as a ventilating device. This may be accomplished by the depression of the seat in a well known way, but I have found that such automatic actuation results very frequently in a great waste of water, and where the water service is metered, as is now the case in many large cities, it is particularly desirable to avoid unnecessary consumption of water. I prefer, therefore, to effect this operation of the closet, as well as the subsequent flushing operation by a manual device, although I wish it understood that the operation may be controlled auto-

matically by the seat, if desired. In effecting the control and proper distribution of the water for the preliminary action of ventilating and wetting down operation, and for 5 the subsequent flushing operation, I prefer to employ a valve mechanism such as is illustrated herein. In the form shown, 17 represents the main body of the valve casing, which is provided internally with a vertical 10 partition, 47, having a threaded aperture formed therein to receive a detachable sleeve, 48, which is screwed therein and which carries at its front end a lateral diaphragm supporting flange, 49. The front portion of 15 the valve casing is provided with a detachable cover, 50, between which and the main body is a diaphragm, 51, the edges of which are clamped between the cover and the main body of the valve casing. The central portion 20 of the diaphragm carries a reciprocating valve stem, 52, secured to the diaphragm and extending through the sleeve, 48, the said stem being hollow and provided internally with a loosely mounted pin, 53, shown 25 in detail in Fig. 9, and provided at its forward end with a washer, 54, secured thereto by means of a screw, 55, the inner face of the washer, 54, being recessed or serrated in order that there may be maintained at all 30 times a passage for water around the stem, 53, from the rear portion of the valve casing to the cavity in the cover, 50, forward of the diaphragm, and indicated at 56, which forms the back pressure chamber of the 35 valve mechanism. The rear portion of the valve body is provided with an inlet aperture, 57, extending through a threaded boss, 58, to which the water supply pipe may be secured, and within the aperture inside of 40 the boss, 58, I preferably provide a screw sleeve, 59, provided on its inner end with the valve seat, 60, adapted to be engaged by a valve, 61, carried on the valve stem, 52, when the latter is in its innermost position, as 45 shown in Fig. 4. A similar valve seat, indicated at 62, is provided on the inner end of the sleeve, 48, and is adapted to be engaged by a valve, 63, also carried on the valve stem, 52, when the valve mechanism is 50 in the position indicated in Fig. 5, with the stem at its extreme outermost position. The valve casing is also provided with a horizontal partition, indicated at 64, above which is formed the outlet chamber, 65, which communicates 55 through apertures, 66, in the sleeve, 48, with the interior of said sleeve, and which is shut off from the inlet aperture, 57, by the horizontal partition, 64. In this outlet chamber, 65, I preferably form a 60 spider, indicated at 67, see Figs. 4, 5 and 6, which is provided centrally with the threaded sleeve portion, 19, into which one end of the clamping tube, 18, is screwed, as hereinbefore described. The outlet chamber, 65, is also provided with an outlet aperture into 65 which the maximum outlet pipe, 16, is screwed or otherwise connected, as previously described. For the purpose of effecting a connection between the tube, 18, which forms the minimum supply passage 70 for the rim flush, and the water inlet chamber 68, of the valve mechanism, I find it convenient to drill a hole, indicated at 69, vertically through the spider, 67, and to insert therein an adjusting screw, 70, as shown, the 75 valve casing being conveniently provided with a coaxial countersunk hole, 71, to receive a screw plug, 72, flush with the upper surface of the valve casing to prevent accidental disturbance of the adjusting screw, 70. 80 The lower part of the passage, 69, will afford a direct connection between the water inlet chamber and the minimum water supply pipe, 18, which supply can be regulated by means of the adjusting screw, 70. The cap or 85 cover, 50, of the valve is provided with a relief aperture for the back pressure chamber, 56, indicated at 73, and controlled by a relief valve, 74. This relief valve, as before stated, may be operated automatically by the depression of the closet seat, or, as in this instance, arranged for manual operation. To 90 this end the relief valve is secured to a plunger, 75, having a disc portion, 76, at its outer end, which is normally held by a 95 spring, 77, in engagement with a disc, 78, on the handle, 79, these parts being maintained in position by a cap, 80, screwed into an aperture in the outer end of the cover, the 100 plunger being provided with a small diaphragm, 81, to prevent leakage. The cover, 50, is also provided with a relief passage, indicated at 82, communicating by small pipe, 83, with the interior of the outlet chamber, 105 in this instance through an aperture, 84, in the spider, so that on the opening of the relief valve, 73, the contents of the back pressure chamber can be discharged. The bottom of the water inlet chamber, 68, is provided with a connection, 85, for the attachment 110 of a pipe, 86, leading to the fitting, 38, of the ventilating jet.

The operation of the apparatus is as follows: Assuming that the water inlet of the valve casing is connected to the water supply, as by pipe, 87, see Fig. 1, and the parts of the valve being in the position indicated in Fig. 4, the inlet valve, 61, will be closed upon the seat, 60, so that no water can enter the valve casing, it being understood that a sufficient quantity of water to fill the back pressure chamber, 56, is passed through the stem, 52, between it and the pin, 53, so that the initial pressure of the water is exerted 115 against the outer face of the diaphragm, 51, which, having a greater area than that of the valve, 61, the latter is held closed. By moving the handle, 79, laterally in any direction, the back pressure valve, 73, will be 120 opened, permitting the escape of water 125 130

therefrom to the outlet chamber, and the pressure of the water in the inlet pipe will immediately force the valve stem forwardly with the entering water and close the valve, 53, against the seat, 62, on the end of the sleeve, 48, thus shutting off all communication between the inlet and the maximum supply passage, 16, for the rim flush. The entering water will be discharged simultaneously to the jet through the connection, 85, and pipe, 86, and also upwardly through the passage, 69, to the minimum supply passage, 18, for the rim flush, and the water carried thereby will be projected, as shown in Fig. 10 2, through the lateral aperture, 24, in the pipe, 18, and through the communicating aperture, 15, in the rear wall of the rim flush passage into the passage, 11, a small volume being delivered which will be held 15 back by the dams, 13, and discharged through the rearmost discharge apertures, 12, between said dams and the aperture, 15, to wet down the rear wall of the bowl while the jet projects a strong injector stream 20 longitudinally of the discharge passage, 25, carrying out of the bowl the water normally maintained therein to form the water seal, indicated by the dotted line in Fig. 2, and thereafter withdrawing large volumes 25 30 of air from the interior of the bowl and performing a perfect ventilating function. This ventilating function is under the control of the user and may be continued for any desired length of time by simply holding the handle in its deflected position. It may be performed at any time and continued with the effect of ventilating the room in which the closet is located, or it may be employed for a few seconds only as may be 35 desired, especially where economy of water 40 is an object.

As soon as the handle is released it returns to normal position under the action of the spring, 77, upon the plunger, 75, and the relief valve is closed, whereupon pressure immediately begins to build up in the back pressure chamber, 56, by reason of the passage of water through the valve stem between it and the loosely mounted pin, 53, 45 and the pressure acting upon the outer face of the diaphragm, causes a slow movement of the valve stem rearwardly toward its closing position. The first movement of the valve stem unseats the valve, 63, from 50 its seat, 62, thus allowing water to pass through the sleeve, 48, and through the apertures, 66, in the lateral walls of the sleeve to the maximum water passage, 16, communicating with the transverse passage, 14, in the bowl, and thus giving a full volume 55 of water which enters the rim passage, 11, through the aperture, 15, in sufficient volume to overflow the dams, 13, and to force through all of the discharge apertures, 12, 60 and all the way around the bowl with initial

pressure, while a portion of the water passes through the vertical passage, 27, and is discharged upwardly and rearwardly through the outlet, 28, thereof, in substantially the same direction as the jet to assist the action 70 of the jet and flushing water in driving out the entire contents of the bowl and thoroughly cleansing the same. As the valve, 61, approaches its seat, 60, the supply of water is cut-off gradually, thus stopping the 75 flushing action and allowing the last portions of the water to enter under restricted pressure so as to insure the refilling of the bowl to the point indicated by the dotted line in Fig. 2 to seal the same. It will thus 80 be seen that when the valve mechanism is operated by the lateral movement of the handle, 79, the water is admitted simultaneously to the jet and to the minimum supply passage for the rim, while the connection 85 with the maximum supply passage is maintained closed. On the return movement of the valve, when the handle is released, the water is admitted to the maximum supply passage for the rim and simultaneously to 90 the minimum supply passage and to the jet, thus giving the fullest possible flushing operation during the return movement of the valve.

88 represents the usual closet seat which 95 is provided with hinge members, 89, pivotally connected to ears 5^a, formed on the securing nuts 5 for the rear flange of the bowl, as shown in Fig. 2. 90 represents the seat cover having a hinged member, 91, 100 also pivotally connected by the same bolt, indicated at 92, to the ears, 5^a, and the seat cover is preferably provided with buffers of rubber, indicated at 93, to engage the upper surface of the rear flange of the bowl, 105 as indicated in dotted lines in Fig. 2, when in vertical position.

What I claim and desire to secure by Letters Patent is:

1. In a water closet, the combination with 110 a bowl provided with a flushing rim passage having a plurality of discharge apertures, said passage being provided with dams of less height than the passage for separating certain of said discharge apertures from 115 the others, means for admitting a small volume of water to the rim passage between said dams, and means for admitting a larger volume of water to said passage to overflow said dams and discharge through all 120 of said discharge passages.

2. In a water closet, the combination with 125 a bowl provided with a flushing rim passage, having a plurality of discharge apertures, said passage being provided at opposite sides of the bowl with dams of less height than the passage, located between the front and rear of the bowl, means for admitting a small volume of water to said rim passage between said dams to be dis- 130

charged through a portion only of the discharge apertures, and means for admitting a larger volume of water to said rim passage, to overflow said dams, and be discharged through all of said apertures.

3. In a water closet, the combination with a bowl provided with a flushing rim passage having a plurality of discharge apertures, said passage being provided with dams of less height than the passage for separating certain of said discharge apertures from the others, said bowl being provided with a minimum supply passage for delivering a small volume of water to the rim passage between said dams, and an independent maximum supply passage for delivering a large volume of water to the rim to overflow said dams and discharge through all of said discharge apertures, and means for independently regulating the volume of water passing through said minimum passage.

4. In a water closet, the combination with a bowl provided with a flushing rim passage having a plurality of discharge apertures, said passage being provided with dams of less height than the passage for separating certain of said discharge apertures from the others, said bowl being provided with a minimum supply passage for delivering a small volume of water to the rim passage between said dams, and an independent maximum supply passage for delivering a large volume of water to the rim to overflow said dams and discharge through all of said discharge apertures, said bowl being provided with a discharge outlet passage and a ventilating jet inlet in the bottom in substantial alignment with the discharge outlet passage, and means for supplying water simultaneously to the jet inlet, and said minimum supply passage for the rim, while maintaining the maximum supply passage of the rim inoperative, to ventilate the bowl and flush a portion of the wall thereof on one side of a line connecting said dams.

5. In a water closet, the combination with a bowl provided with a flushing rim passage, having a plurality of discharge apertures, said passage being provided at opposite sides of the bowl with dams of less height than the passage, located between the front and rear of the bowl, a minimum water supply passage for delivering a small volume of water to said rim in rear of said dams, to be distributed through the discharge apertures in rear of said dams, a maximum water supply passage for delivering the full flushing volume of water to said rim to overflow said dams, and be distributed by all the discharge apertures of the rim, said bowl being provided with a discharge passage, a ventilating jet inlet in the bottom of the bowl in substantial alignment with the discharge passage, of a jet nozzle comprising a metallic spud having a flanged portion at its inner end and a tubular stem extending through said aperture, clamping means secured to said stem for securing a tight joint with the bowl, and means for connecting a supply pipe to said spud outside of the bowl.

simultaneously admitting water to the jet inlet and to said minimum rim supply passage, while holding said maximum rim supply passage out of operation, to break the water seal and effect a ventilating action 70 while keeping the rear end of the bowl moistened, and for admitting water simultaneously to said maximum rim passage and to said jet simultaneously to flush the bowl.

6. In a water closet, the combination with a bowl provided with a flushing rim passage, having a plurality of discharge apertures, said passage being provided at opposite sides of the bowl with dams of less height 80 than the passage, located between the front and rear of the bowl, a minimum water supply passage for delivering a small volume of water to said rim in rear of said dams to be distributed through the discharge apertures in rear of said dams, a maximum water supply passage for delivering the full flushing volume of water to said rim to overflow said dams and be distributed by all the discharge apertures of the rim, said bowl being 90 provided with a discharge passage, a ventilating jet inlet in the bottom of the bowl in substantial alignment with said discharge passage, means for simultaneously admitting water to the jet inlet and to said minimum 95 rim supply passage, while holding said maximum rim supply passage out of operation to break the water seal and effect a ventilating action while keeping the rear wall of the bowl moistened, and for admitting water to both of said rim supply passages and to said jet inlet simultaneously to flush the bowl.

7. In a water closet, the combination with a bowl provided with a flushing rim passage, having a plurality of discharge apertures, said passage being provided at opposite sides of the bowl with dams of less height than the passage, located between the front and rear of the bowl, a maximum rim supply passage 110 connected with the rim passage for supplying water in sufficient quantity to overflow said dams and be distributed through all of said discharge apertures, and a minimum supply passage extending axially through 115 the maximum passage and provided with a lateral discharge aperture for supplying a small volume of water to the rear portion of said rim between said dams.

8. In a water closet, the combination with 120 a bowl provided with flushing means and a discharge passage, and having a jet aperture in substantial alignment with the discharge passage, of a jet nozzle comprising a metallic spud having a flanged portion at its inner 125 end and a tubular stem extending through said aperture, clamping means secured to said stem for securing a tight joint with the bowl, and means for connecting a supply pipe to said spud outside of the bowl.

9. In a water closet, the combination with a bowl provided with flushing means and a discharge passage, and having a jet aperture in substantial alignment with the discharge passage, of a jet nozzle comprising a metallic spud having a flanged portion at its inner end and a tubular stem extending through said aperture, clamping means secured to said stem for securing a tight joint with the bowl, means for connecting a supply pipe to said spud outside of the bowl, and means accessible from the exterior of the bowl for regulating the discharge of water from the jet nozzle in accordance with the available water pressure.

10. In a water closet, the combination with a bowl provided with flushing means and a discharge passage, and having a jet aperture in substantial alignment with the discharge passage, of a jet nozzle comprising a metallic spud having a flanged portion at its inner end and a tubular stem extending through said aperture, clamping means secured to said stem for securing a tight joint with the bowl, means for connecting a supply pipe to said spud outside of the bowl, and a removable regulating device, located in said spud, and accessible and removable from the exterior of the bowl, for regulating the discharge of water from the jet nozzle in accordance with the available water pressure.

11. In a water closet, the combination with a bowl provided with flushing means and a discharge passage, and having a jet aperture in substantial alignment with the discharge passage, of a jet nozzle comprising a metallic spud having a flanged portion at its inner end and a tubular stem extending through said aperture, clamping means secured to said stem for securing a tight joint with the bowl, means for connecting a supply pipe to said spud outside of the bowl, and a removable regulating device, comprising a throttling member located in the discharge passage through said stem, and a retaining member engaging and detachably secured to said stem, and accessible from the exterior of the bowl.

12. In a water closet, the combination with a bowl provided with flushing means and a discharge passage, and having a jet aperture in substantial alignment with the discharge passage, of a jet nozzle comprising a metallic spud having a flanged portion at its inner end and a tubular stem extending through said aperture, clamping means secured to said stem for securing a tight joint with the bowl, means for connecting a supply pipe to said spud outside of the bowl, said spud having an aperture opening outside of the bowl, and a removable jet regulating device, adapted to be inserted and removed through said aperture, and comprising a throttling member for throttling the discharge of water

through said spud, and a securing member secured to said spud and closing said exterior aperture.

13. In a water closet, the combination with a bowl provided with flushing means and a discharge passage, and having a jet aperture in substantial alignment with the discharge passage, of a jet nozzle comprising a metallic spud having a flanged portion at its inner end and a tubular stem extending through said aperture, clamping means secured to said stem for securing a tight joint with the bowl, means for connecting a supply pipe to said spud outside of the bowl, said spud having an aperture opening outside of the bowl, the walls of said aperture being threaded, and a removable jet regulating device adapted to be inserted and removed through said aperture, and comprising a throttling member engaging the discharge aperture of the spud, and a threaded securing member engaging the threaded portion of the walls of said aperture, said regulating device being provided at its outer end with means for enabling it to be rotated.

14. In a water closet, the combination with a bowl provided with flushing means, a discharge passage and an aperture for the reception of a jet nozzle in substantial alignment with the said passage, of a hollow spud secured in said aperture and having a hollow stem portion extending outside of said bowl, and provided with lateral apertures, of a fitting provided with a sleeve portion surrounding the laterally apertured portion of said stem, and with means for connecting a water pipe thereto, said sleeve being rotatable about said stem, and means for clamping said sleeve in operative relation with said stem.

15. In a water closet, the combination with a bowl provided with flushing means, a discharge passage and an aperture for the reception of a jet nozzle in substantial alignment with the said passage, of a hollow spud secured in said aperture and having a hollow stem portion extending outside of said bowl, and provided with lateral apertures, of a fitting provided with a sleeve portion surrounding the laterally apertured portion of said stem, and with means for connecting a water pipe thereto, said sleeve being rotatable about said stem, and means for clamping said sleeve in operative relation with said stem, said stem having an exterior aperture outside of said sleeve, and a removable regulating device provided with a throttling member engaging the discharge aperture of said spud, and a threaded member for engaging said exterior aperture.

16. In a water closet, the combination with a bowl provided with flushing means, a discharge passage and an aperture for the reception of a jet nozzle in substantial align-

ment with the said passage, of a hollow spud secured in said aperture and having a hollow stem portion extending outside of said bowl, and provided with lateral apertures, of a fitting provided with a sleeve portion surrounding the laterally apertured portion of said stem, and provided with means for connecting a water pipe thereto, said sleeve being rotatable about said stem, and means for clamping said sleeve in operative relation with said stem, said stem having a threaded aperture in its outer end, and a removable regulating device provided with a throttling member for engaging the discharge aperture of said spud, a threaded securing member for engaging said threaded exterior aperture, and a connecting stem extending between the throttling head and securing device and constructed to afford passage of water between it and the laterally apertured portion of the spud.

17. In a water closet, the combination with a bowl provided with flushing means, a discharge passage and an aperture for the reception of a jet nozzle in substantial alignment with the said passage, of a hollow spud secured in said aperture and having a hollow stem portion extending outside of said bowl, means for delivering water to the interior of said stem, said stem having a threaded aperture adjacent to its outer end, and a removable regulating device comprising a throttling member provided with reduced apertures located in the discharge aperture of the spud, a threaded securing member engaging said threaded aperture, and a connecting portion of reduced cross sectional area between said throttling member and said securing member.

18. In a water closet, the combination with a bowl provided with flushing means, a discharge passage and an aperture for the reception of a jet nozzle in substantial alignment with the said passage, of a hollow spud secured in said aperture and having a hollow stem portion extending outside of said bowl, said stem having a threaded aperture in its outer end, a removable regulating device having a throttling member engaging the discharge aperture of the spud, a securing member threaded in the aperture at the outer end of the stem, and a connecting member of reduced cross sectional area, extending from said throttling member to said securing member, and a cap engaging an exterior threaded portion of the spud adjacent to its outer end, for enclosing the same and for holding said sleeve in operative relation with the spud.

19. In a water closet, the combination with a bowl provided with a rim flushing passage and a transverse water supply passage therefor extending across the bowl and providing openings at the opposite sides thereof,

a controlling valve casing provided with a supply pipe connected to one end of the said transverse passage by means effecting the closing of the same, a transversely disposed connecting member secured at one end to 70 the valve casing, extending longitudinally through said transverse passage of the bowl, and a closure secured to the opposite end of said transverse connecting member and closing the opposite end of said transverse 75 passage.

20. In a water closet, the combination with a bowl provided with a rim flushing passage and a transversely disposed supply passage, extending entirely across the bowl and opening at its opposite ends, and communicating with said rim passage, a valve casing having a maximum water supply pipe connected with and closing one end of said transverse passage, a hollow connecting pipe secured at one 85 end of the valve casing, extending through said transverse passage of the bowl, clamping means engaging the opposite end of said connecting pipe for closing the same and for closing the adjacent end of said transverse 90 passage, said connecting pipe being provided with minimum discharge apertures in alignment with the communication between said transverse passage and said rim passage, and controlling valves in said valve 95 casing for said maximum and minimum supply pipes.

21. In a water closet, the combination with a bowl provided with a rim flushing passage having discharge apertures extending around 100 the bowl, said passage being provided on opposite sides between the front and rear of the bowl with dams of less height than the passage itself, said bowl being provided with a transverse passage extending entirely 105 across the bowl and opening at opposite sides thereof, a valve casing having a maximum water supply pipe connected with said transverse passage and closing one end of the same, a minimum supply pipe having one 110 end connected to the valve casing, said pipe extending coaxially through said transverse passage, clamping devices engaging the opposite end of said minimum supply pipe, for closing said pipe and said transverse 115 passage at the opposite end thereof, said minimum supply pipe being provided with a discharge aperture in line with the communication between said transverse passage and the rim passage, and valves in said valve 120 casing for controlling the admission of water to said minimum and maximum supply pipes.

22. In a water closet, the combination with a bowl provided with a rim flushing passage 125 having discharge apertures extending around the bowl, said passage being provided on opposite sides between the front and rear of the bowl with dams of less height than the passage itself, said bowl being provided 130

- with a transverse passage extending entirely across the bowl and opening at opposite sides thereof, a valve casing having a maximum water supply pipe connected with 5 said transverse passage and closing one end of the same, a minimum water supply pipe having one end connected to the valve casing, said pipe extending coaxially through said transverse passage, clamping devices 10 engaging the opposite end of said minimum supply pipe, for closing said pipe and said transverse passage at the opposite end thereof, said minimum supply pipe being provided with a discharge aperture in line with 15 the communication between said transverse passage and the rim passage, said bowl being provided with a discharge passage and a ventilating jet in substantial alignment therewith, a connection from said valve casing 20 to said jet, and valves in said valve casing for controlling the admission of water to said minimum supply pipe and to said maximum supply pipe, and to said jet.
23. In a water closet, the combination with 25 a bowl, provided with a rim flushing passage having dams located on opposite sides, of less height than the passage, said bowl having a discharge passage and a ventilating jet in substantial alignment therewith, of a 30 valve casing provided with a water inlet, a central partition, a back pressure chamber, and a diaphragm forming one wall of the back pressure chamber, a movable valve stem connected with said diaphragm and 35 extending through an aperture in said partition and provided with an inlet valve normally closing said water inlet, and a valve for closing the aperture in the partition when the valve is in open position, said 40 valve casing having a minimum supply passage communicating with the rim passage, and a maximum supply passage connected to the rim passage and connected to the valve casing on the opposite side of the partition from the minimum supply passage, and a connection from the jet to the valve 45 casing on the same side of said partition as the minimum supply passage, a relief valve for the back pressure chamber, and means 50 for maintaining communication at all times between the water inlet and the back pressure chamber.
24. In a water closet, the combination with a flushing valve, provided with a central partition interposed between the inlet and 55 outlet chambers thereof, the water supply passage communicating with the inlet chamber, a back pressure chamber, a diaphragm forming one wall thereof, a minimum rim 60 flushing passage connected with said inlet chamber, a maximum rim flushing passage connected with the outlet chamber, a valve stem connected to the diaphragm and extending through an aperture in the partition 65 an inlet valve carried thereby for closing the inlet passage, and a valve carried thereby for closing the aperture in said partition when the valve is in open position, a relief valve for the back pressure chamber, and means for maintaining communication at all times between the water inlet passage and the back pressure chamber, and a regulating device for regulating the flow of water through the minimum supply passage for the flushing rim.
27. In a water closet, the combination with a flushing valve, provided with a central partition interposed between the inlet and outlet chambers thereof, a water supply passage communicating with the inlet chamber, a back pressure chamber, a diaphragm forming one wall thereof, a minimum rim 120 flushing passage connected with said inlet chamber, a maximum rim flushing passage connected with the outlet chamber, a valve stem connected to the diaphragm and 125 extending through an aperture in the partition, an inlet valve carried thereby for closing the inlet passage, and a valve carried thereby for closing the aperture in said partition when the valve is in open position, a relief valve for the back pressure chamber, and means for maintaining communication at all times between the water inlet passage and the back pressure chamber, and a valve stem connected to the diaphragm and 130

extending through an aperture in the partition, an inlet valve carried thereby for closing the inlet passage, and a valve carried thereby for closing the aperture in said partition when the valve is in open position, a relief valve for the back pressure chamber, and means for maintaining communication at all times between the water inlet passage and the back pressure chamber, an aperture 10 extending from the exterior of the valve cas-

ing to the minimum supply passage for the flushing rim, and a threaded regulating device located therein for regulating the flow of water through said minimum supply passage and for closing said aperture, whereby said regulating device is accessible from the exterior of the valve casing. 15

In testimony whereof I affix my signature.

PHILIP HAAS.
